CLAIM

The ornamental design for a bath brush, as shown and described.

DESCRIPTION

FIG. 1 is a perspective view of the top, side and one end of a bath brush showing my new design, the opposite end being a mirror image thereof;

FIG. 2 is a side elevational view of the brush head only,
the opposite side being a mirror image and shown separately for clarity of illustration;

FIG. 3 is a side elevational view of FIG. 1, the opposite side being a mirror image;

FIG. 4 is a bottom plan view thereof; and,

FIG. 5 is a top plan view thereof.
